WILLIAM P. HILL

By Ralph Taenik ATTORNEY.

UNITED STATES PATENT OFFICE.

WILLIAM P. HILL, OF ST. LOUIS, MISSOURI.

BURNER-TIP.

1,304,045.

Specification of Letters Patent. Patented May 20, 1919.

Application filed August 9, 1918. Serial No. 249,116.

To all whom it may concern:

Be it known that I, WILLIAM P. HILL, a citizen of the United States, residing at the city of St. Louis, State of Missouri, have 5 invented a certain new and useful Improvement in Burner-Tips, of which the following is a specification, reference being had to the accompanying drawing, forming a part thereof.

10 This invention relates to a certain new and useful improvement in burner tips.

In the use of vapor burners or the like as at present generally constructed the jet-orifices thereof very frequently become 15 clogged by particles of foreign matter carried along with the discharging gas or vapor, resulting in interruption of operations and in considerable inconvenience of the user. The principal object of my present 20 invention is to provide a simple and inexpensive burner-nipple or tip having a jet-orifice and a guard for efficiently protecting the jet-orifice from becoming clogged by foreign matter carried by the discharging 25 vapor or gas.

With the above and other objects in view, my invention resides in the provision of a burner-nipple or tip having a jet-orifice and a jet-orifice guard preferably in the shape 30 of a more or less elongated tube, the tube being in open discharge communication with the jet-orifice and being provided with a plurality of intake or entrance-ports disposed for the most part at an angle to the trend of movement of the gas or vapor and each having an area less than the area of 35 the jet-orifice, the disposition of the several intake-ports and their relative area obviating clogging of the jet-orifice by particles of 40 foreign matter carried by the escaping gas or vapor; and in certain novel features of form, construction, and combination of parts, all as will hereinafter be described and afterward pointed out in the claims.

45 In the accompanying drawing,

Figure 1 is an elevational view of a burner-nipple or tip embodying my invention;

Fig. 2 is a plan view of the same;

50 Fig. 3 is an inverted plan view of the nipple;

Fig. 4 is a longitudinal sectional view of the nipple in operative position upon the discharge-end of a burner-jet or pipe also 55 shown in longitudinal section;

Fig. 5 is a view similar to Fig. 4, but

taken at an angle of approximately ninety degrees relatively thereto; and

Fig. 6 is a sectional view approximately on the line 6—6, Fig. 4.

Referring to the said drawing, in which like reference characters refer to like parts throughout the several views, 1 indicates the discharge-pipe or jet of a gas or vapor burner, which is arranged for communication with a source of gas or vapor fuel supply, not shown.

Threaded, as shown, or otherwise seated upon the discharge-end of the pipe or jet 1, is the nipple or tip 2, which is substantially 70 a cup-shaped body provided approximately centrally in its end wall 3 with a jet-orifice 4. Preferably the nipple or tip 2 is externally of non-circular formation to facilitate its connection with, or disconnection 75 from, the jet or pipe 1.

5 indicates the orifice-guard, which, as here shown, is preferably in the form of a tube disposed axially lengthwise of the nipple 2 and in open communication at its one 80 end 6 with the jet-orifice 4, tube 5 being seated and soldered, brazed, or otherwise fixed at its end 6 in a counter-bore 7 provided in the end wall 3 of the nipple at the inner end of the jet-orifice 4, as shown. A 85 relatively firm union and, at the same time, a non-leaking joint is thereby provided between the nipple 2 and the tube or guard 5, whereby gas or vapor discharging through jet or pipe 1, as well as also particles of carbon or other foreign matter carried by such discharging gas or vapor and lodging against the surrounding portion of the end wall 3 of the nipple or tip, are prevented 90 from entering the tube 5 at its said end 6. 95

At its other or free end, the tube 5 is restricted, as shown, by pinching or otherwise, as at 8, to the extent of providing an intake-slot or entrance-port 9 of such small size or area relatively to the size or area of 100 jet-orifice 4 as to preclude or prevent the admission or entrance into the tube 5 of a gas or vapor-carried particle of foreign matter having a size greater than the size or area of the jet-orifice 4. Adjacent its said 105 other or free end, and at a suitable distance from the end wall 3 of nipple 2, the tube 5 is also provided with a plurality of intake-openings or entrance-ports 10, each disposed approximately at right angles to tube 5 and 110 hence also approximately at right angles to the trend of movement or travel of the gas

or vapor discharging through the burner-jet or pipe 1. The several entrance or intake-ports 10 being so disposed relatively to the tube 5 and the gas-travel in burner-pipe 1, there is little, if any, tendency for gas or vapor-carried foreign-matter, such as particles of carbon and the like, to lodge therein or to pass therethrough into the tube 5. Since, however, each port 10, as well as 10 the port 9, is of lesser area than the jet-orifice 4, any foreign matter which may pass or enter through any of said ports into the tube 5 will at once pass outward with or be carried outward by the gas or vapor escaping or discharging through the jet-orifice 4. I thus in a very simple manner efficiently obviate clogging of the jet-orifice 4, the entrance into the tube 5 of any particle of gas or vapor-carried foreign matter large 20 enough to obstruct the jet-orifice 4 being prevented by the several intake or entrance-ports 9 and 10. The combined area of the several entrance or intake-ports 9 and 10 is preferably greater than the total area of the 25 jet-orifice 4; consequently, should one or more of said intake or entrance-ports become clogged by gas or vapor-carried foreign matter, the remaining unobstructed ports will permit the flow through tube 5 30 to the jet-orifice 4 of the required, or at least a sufficient amount of gas or vapor for operating purposes.

The tube 5 is preferably of such length relatively to the flange or side wall of nipple 2 that its several ports 9 and 10 will be located preferably at a suitable distance from the inner face of nipple end-wall 3, so that there is little, if any, liability of the several ports becoming clogged by carbon or 40 other foreign matter carried along with the gas or vapor and accumulating against the inner face of the nipple end-wall 3 and in the discharge-end of the jet or burner 1. And in this connection, I may state that the 45 jet-orifice 4 may be a drilled hole of one dimension or area and the several ports 10 may be drilled holes of a lesser dimension or area than that of the jet-orifice 4.

Having thus described my invention, what I claim and desire to secure by Letters Patent is:

1. As a new article of manufacture, a burner-tip consisting of a cup-shaped body-member having a jet-orifice in its end wall, and a clog-preventing guard for the jet orifice, the guard comprising an elongated tube of reduced diameter throughout its length relatively to the diameter of the body-member end-wall, the tube being disposed axially of and within the body-member and 55 fixed at one end to the body-member end-wall in communication with the jet-orifice, the tube having an intake-port located in its side wall adjacent its said opposite end.

2. As a new article of manufacture, a burner-tip consisting of a cup-shaped body-member having a jet-orifice in its end wall, and a clog-preventing guard for the jet-orifice, the guard comprising an elongated tube of reduced diameter throughout its 70 length relatively to the diameter of the body-member end-wall, the tube being disposed axially of and within the body-member and 75 fixed at one end to the body-member end-wall in communication with the jet-orifice, the tube being restrictedly closed at its opposite end and provided with a plurality of intake-ports located in its side wall adjacent its said opposite end.

3. In combination with a burner-pillar, of 80 a cup-shaped tip fitting thereupon, the tip having an end-wall provided with a jet-orifice, and a guard for the jet-orifice comprising an elongated tube of reduced diameter throughout its length relatively to 85 the diameter of the tip end-wall, the tube being disposed axially of and within the pillar and tip and fixed at one end to the tip end-wall in communication with the jet-orifice, the tube having in its wall an intake- 90 port whose axis is disposed at an angle to the trend of gas-movement in the pillar.

In testimony whereof, I have signed my name to this specification.

WILLIAM P. HILL.
